UNITED STATES PATENT OFFICE.

WILLIAM R. McHILL, OF MORAN, KANSAS.

OIL-BURNER.

1,275,453.

Specification of Letters Patent. Patented Aug. 13, 1918.

Application filed April 23, 1918. Serial No. 230,304.

To all whom it may concern:

Be it known that I, WILLIAM R. McHILL, a citizen of the United States, residing at Moran, in the county of Allen and State of 5 Kansas, have invented a new and useful Oil-Burner, of which the following is a specification.

The device forming the subject matter of this application is a burner adapted to 10 handle crude oil and like fuels, and the invention aims to provide, in a device of the kind specified, novel means whereby a thorough mixture of oil and gas will be brought about. Another object of the invention is 15 to provide novel means whereby the fuel will be thoroughly vaporized.

A further object of the invention is to provide novel means whereby the flame will be protected from drafts. The invention 20 aims to provide a structure of the kind mentioned which will burn clean, and give a hot blue flame, with a minimum expenditure of fuel.

It is within the province of the disclosure 25 to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that, within 30 the scope of what is claimed, changes in 35 the precise embodiment of the invention shown can be made without departing from the spirit of the invention.

In the accompanying drawings:—

Figure 1 shows in vertical section, a device 40 constructed in accordance with the invention; Fig. 2 is a fragmental top plan of the pan; Fig. 3 is a fragmental top plan of the air baffle.

The device forming the subject matter of 45 this application includes an annular pan 6 which may be supported in any suitable way in a stove, furnace or other container. The pan 6 comprises a bottom 40, an upstanding marginal flange 41 and a central tube 42, 50 across which extends a cross bar 17, including a hub 19. Openings 18 exist on each side of the cross bar 17. The tube 42, the flange 41 and the bottom 40 of the pan form an annular trough 43. A wick 7, preferably 55 made of asbestos, is located in the trough 43 and surrounds the central tube 42 closely.

Disposed below the pan 6 is a baffle plate 5 having a circumscribing rim 28 and provided with upstanding lugs 23 attached to the bottom 40 of the pan 6 by means of securing devices 16. A fuel supply conduit is provided, the same including a pipe 4 passing through the baffle plate 5, and through the hub 19 of the cross bar 17. By means of an elbow 3, the pipe 4 is connected 60 to a pipe 2 carrying a valve 1 to which the fuel is supplied, preferably under pressure. The particular arrangement of piping used will depend, of course, on the nature of the structure wherewith the device forming the 65 subject matter of this application is assembled.

The invention comprises a lower spreader plate 8 disposed above the tube portion 42 of the pan 6 and spaced therefrom, the 70 spreader plate including a neck 44 threaded on the upper end of the pipe 4 and supported on the hub 19 of the cross bar 17. The lower spreader plate 8 is supplied with a depending lip 29 located directly above the wick 7. 75 A pipe 12 is threaded into the lower spreader plate 8 and its neck 44 and is provided at its upper end with notches 14.

The numeral 10 denotes a dome having an internal collar 15 receiving the upper end 80 of the pipe 12, the dome being supported removably on the upper end of the pipe.

The dome 10 has an upstanding ear 73 provided with an opening 30, adapted to receive a hook or the like, whereby the dome 90 10 may be lifted off the upper end of the pipe 12 at any time, to permit a cleaning of the device. The lower edge of the dome 10 lies slightly below the upper surface of the lower spreader plate 8. A vaporizing tube 95 11 surrounds the pipe 12 and is spaced therefrom as shown at 27, the upper end of the vaporizing tube being threaded into the collar 15 of the dome 10. The lower end of the vaporizing tube 11 is threaded into a 100 boss 20, constituting a part of an upper spreader plate 9, disposed above the lower spreader plate 8, the spreader plates being separated slightly, as shown at 26.

In practical operation, the valve 1 is 105 opened and the fuel passes through the conduit which comprises the pipes 2, 4 and 12 and flows through the notches 14 into the space 27 between the pipe 12 and the vaporizing tube 11. Thence the oil flows, through 110 the space 26 between the spreader plates 8 and 9 and thence onto the wick 7. In this

connection it is to be observed that the lip 29 on the plate 8 serves to prevent the oil from running backwardly along the under surface of the plate, and serves, also, to direct the oil downwardly onto the wick 7. The valve 1 is then closed, and the oil on the wick 7 is ignited, the spreader plates 8 and 9 being heated and the vaporizing tube 11 being heated, so that the oil as it flows downwardly in the space 27 between the tube 11 and the pipe 12, will be converted into gas. The valve 1 may then be opened to secure the desired feed of oil, and to regulate the flame which, of course, burns at the peripheries of the plates 8 and 9. The air passes upwardly through the openings 18 on each side of the cross bar 17 and facilitates combustion, it being noted that the baffle plate 5 serves to direct the air beneath the pan 6, and to hold the air beneath the pan, to some extent, so that the air is heated before it passes upwardly through the openings 18. The dome 10 extends downwardly below the space 26 between the spreader plates 8 and 9, and, consequently, the flame is shielded from the wind and the air and is confined within the dome, so as to promote the combustion.

Excess oil, at the starting of the device, will be received and held in the trough 43, and should any excess oil find its way downwardly onto the baffle plate 5, the oil will be retained by the rim 28 of the baffle plate and will ignite after a short time, thereby heating up the device and aiding in securing a proper vaporization of the oil, as the same flows downwardly between the vaporizing tube 11 and the pipe 12, and between the spreader plates 8 and 9. As hereinbefore explained, the dome 10 may be lifted off the pipe 12 at any time, carrying with it the tube 11 and the spreader plate 9, the device thus being opened up for cleaning or repairs.

Having thus described the invention, what is claimed is:—

1. In a device of the class described, a fuel supply conduit; a dome supported removably by the upper end of the conduit; a vaporizing tube carried by the dome and surrounding a portion of the conduit, the vaporizing tube and said portion of the conduit

being spaced apart; a spreader carried by the lower end of the vaporizing tube; and a second spreader spaced from the first 55 spreader and coöperating therewith, the second spreader being carried by the conduit.

2. In a device of the class described, a pan having a central opening; a baffle disposed below the pan; a fuel supply conduit passing upwardly through the baffle and through the pan; a first spreader plate carried by the conduit and disposed above the opening; a vaporizing tube surrounding the conduit above the spreader plate; means for establishing communication between the upper ends of the conduit and the vaporizing tube; and a spreader plate carried by the lower end of the vaporizing tube and disposed above the first spreader plate. 70

3. In a device of the class described, a pan having a tube; a wick carried by the pan and surrounding the tube; a fuel supply conduit passing upwardly through the tube; a first spreader plate mounted on the conduit and disposed above the tube, the spreader plate having a depending flange located above the wick; a vaporizing tube surrounding the conduit above the spreader plate; means for establishing communication between the upper ends of conduit and the vaporizing tube; and a second spreader plate carried by a vaporizing tube and disposed above the first spreader plate. 75

4. In a device of the class described, a pan having an opening; a baffle disposed below the pan; a fuel supply conduit extended upwardly through the baffle and the pan; a first spreader plate carried by the conduit, the pan having an opening located below the spreader plate; a dome supported removably on the upper end of the conduit; a vaporizing tube carried by the dome and surrounding a portion of the conduit; and a second spreader plate mounted on the vaporizing tube and located above the first specified spreader plate. 80

In testimony that I claim the foregoing as my own, I have hereto affixed by signature in the presence of two witnesses.

WILLIAM R. McHILL.
